US00D911352S

(12) **United States Design Patent** (10) Patent No.: **US D911,352 S**
 Stroier (45) Date of Patent: **** Feb. 23, 2021**

(54) **DISPLAY SCREEN WITH GRAPHICAL USER INTERFACE FOR PRESENTING WEBSITE ANALYTICS**

(71) Applicant: **Siteimprove Inc.**, Bloomington, MN (US)

(72) Inventor: **Christoffer Lund Stroier**, Copenhagen (DK)

(73) Assignee: **Siteimprove A/S**, Copenhagen (DK)

(**) Term: **15 Years**

(21) Appl. No.: **29/621,701**

(22) Filed: **Oct. 10, 2017**

(51) LOC (13) Cl. **14-04**

(52) U.S. Cl. **USPC D14/485**

(57) **CLAIM**

The ornamental design for a display screen with graphical user interface for presenting website analytics, as shown and described.

DESCRIPTION

The FIGURE is a front view of a display screen with graphical user interface for presenting website analytics. The broken lines showing a display screen and elements of the graphical user interface illustrate portions of the article, and form no part of the claimed design. All text, which is also presented with broken lines, forms no part of the claimed design.

1 Claim, 1 Drawing Sheet
